[57] **CLAIM**

The ornamental design of a lamp cartridge for optical character recognition reader, substantially as shown.

DESCRIPTION

FIG. 1 is a perspective view of a lamp cartridge for optical character recognition (OCR) reader, in accordance with my new design;

FIG. 2 is a top plan view of the lamp module shown in FIG. 1;

FIG. 3 is a left side elevational view of the lamp cartridge shown in FIG. 1, the right side, not shown, being a mirror image thereof;

FIG. 4 is a front elevational view of the lamp cartridge shown in FIG. 1;

FIG. 5 is a rear elevational view of the lamp cartridge shown in FIG. 1; and

FIG. 6 is a bottom plan view of the lamp module shown in FIG. 1.
